UNITED STATES PATENT OFFICE.

MARSHALL T. LEVEY, OF INDIANAPOLIS, INDIANA.

CHECK-BOOK.

956,861.

Specification of Letters Patent. Patented May 3, 1910.

Application filed December 30, 1909. Serial No. 535,544.

To all whom it may concern:

Be it known that I, MARSHALL T. LEVEY, a citizen of the United States, residing at Indianapolis, in the county of Marion and

5 State of Indiana, have invented certain new and useful Improvements in Check-Books, of which the following is a specification.

This invention relates to check-books employed by depositors for withdrawing funds 10 from banks, trust companies and like financial institutions; and the object of the invention is to provide a book of the above character which, when not in use, may be folded so as to reduce its length, making it 15 especially convenient for women depositors.

I accomplish the object of the invention by means of the check-book illustrated in the accompanying drawings, forming a part hereof, in which—

20 Figure 1 is a perspective view of a check-book embodying my invention. Fig. 2 is a top or plan view of the check-book. Fig. 3 is a side elevation of the check-book. Fig. 4 is a fragmentary detail view, on an enlarged scale, of one end of said book.

In the drawings, 10 represents the several leaves which serve the purpose of the usual and well known blank checks and, taken collectively, form the check-book. These checks 30 are perforated as shown at 11, so as to provide the usual stubs 12. The check-book is provided with a flexible cover or back-piece 14, which corresponds to the size of the leaves 10. The back 14 is preferably composed of paper, generally of a heavier weight than that forming the leaves 10, and these backs may be suitably embellished on the outer surface to imitate alligator hide, and the like, if desired. Leather or other 35 suitable material in the place of paper may be used to form the backs 14. The check-books are also provided with flaps 17 which are formed of press-board or similar stiff material. These flaps are placed on top of 40 the leaves and at the ends containing the stubs. The flaps 17, leaves 10 and the backs 14 are secured together by stitching or binder's wire 18. The free ends of the flaps 17 form tongues to hold the free ends of the

45 backs 14 and the leaves 10, when the latter are bent over and thrust under said tongues in the manner shown in Fig. 1 of the drawings. The flaps 17 being composed of press-board or like material have considerable 50 rigidity and strength, the nature of the material being such as to resist force having

a tendency to raise the flaps up off of the leaves 10. Hence the flaps form a clamp to tightly press the free ends of the backs 14 and leaves 10 against the underlying surface of the leaves when the free ends of the latter are pushed and become wedged under said flaps. After the back 14, leaves 10 and flaps 17 are secured together by means of the stitching or wire 18, a binder 20, generally 60 formed of woven fabric, is pasted around the end of the book, allowing it to extend across the face of the flaps and a short distance along the back. The binder 20 hides the stitching or wire 18 and imparts 65 a finished appearance to the book.

In closed position the lengths of the check-books are reduced one-half of their original size, so that the space required for carrying them is correspondingly reduced. This 75 feature is especially appreciated by women whose means for carrying various articles is necessarily limited, at the same time the actual size of the checks are retained so as to conform to the size of the bank checks 80 universally in vogue.

Having thus fully described my said invention, what I desire to secure by Letters Patent, is—

1. A check-book comprising a plurality of 85 leaves, a back arranged beneath said leaves, a flap, composed of stiffer material than that employed in the leaves and back, forming a catch for the free ends of the leaves and back when the latter are folded over and 90 pushed thereunder, and a fastener for securing the leaves, back and flap together.

2. A check-book comprising a plurality of leaves, a back arranged beneath said leaves, a flap, composed of stiffer material than that 95 employed in the leaves and back, forming a catch for the free ends of the leaves and back when the latter are folded over and pushed thereunder, a fastener for securing the leaves, back and flap together, and a binder pasted 100 around the fastened ends of the leaves, back and flap and adapted to conceal the fastener and impart a finished appearance to the book.

In witness whereof, I, have hereunto set 105 my hand and seal at Indianapolis, Indiana, this 30th day of November, A. D. one thousand nine hundred and nine.

MARSHALL T. LEVEY. [L. s.]
